COMBINATION PIPE REST AND ARTICLE HOLDING GUARD

Leon Horton, Saginaw, Mich.

Application April 18, 1949, Serial No. 2,113

Term of patent 14 years

(Cl. D85—8)

To all whom it may concern:

Be it known that I, Leon Horton, a citizen of the United States of America, residing at Saginaw, county of Saginaw, and State of Michigan, have invented a new, original, and ornamental Design for a Combination Pipe Rest and Article Holding Guard, of which the following is a specification, reference being made to the accompanying drawing, forming a part thereof.

Figure 1 is a top plan view of a combination pipe rest and article holding guard showing my new design.

Figure 2 is a side plan view thereof, and

Figure 3 is a bottom plan view thereof.

The dominant features of my design are the portions shown in full lines.

I claim:

The ornamental design for a combination pipe rest and article holding guard, as shown and described.

LEON HORTON.
